ELECTRICAL SWITCH GEAR

Charles H. Hill and Kenneth T. Ashdown, Drexel Hill, Pa., assignors to General Electric Company, a corporation of New York

Application July 31, 1935, Serial No. 33,985

5 Claims. (Cl. 175—298)

Our invention relates to electrical switchgear, more particularly to means for interlocking the opening and closing operations of two or more circuit breakers. In certain installations two or 5 more circuit breakers are arranged for alternatively controlling a circuit or circuits. Where circuit conditions require a definite and predetermined order of operation, such as maintaining one breaker open when another breaker is closed, reliable interlocking means must be provided.

The principal object of our invention is the provision of improved circuit breaker controlling and interlocking means for two or more breakers which shall be simple and compact in design and 10 positive and reliable in operation.

Our invention will be more fully set forth in the following description referring to the accompanying drawing, and the features of novelty which characterize our invention will be pointed 15 out with particularity in the claims annexed to and forming a part of this specification.

Referring to the drawing, Fig. 1 is an elevational view, partly in section, of switchgear of the drawout type embodying our invention; Fig. 2 is a simplified plan view, looking downwardly, of 20 part of the interlocking mechanism of the switchgear shown by Fig. 1, and Fig. 3 is a perspective view of the essential elements of the aforesaid interlocking mechanism.

30 Referring to Fig. 1, the draw-out type switchgear illustrated by way of example, comprises a movable truck portion 1 mounted on wheels 2 and a stationary portion or housing 3 in which stationary conductors or busbars of the circuit, or 35 circuits, to be controlled are mounted. The truck 1 is suitably formed of structural steel framework and supports a circuit breaker 4, an oil circuit breaker of conventional design being shown in the present instance.

40 In operation, the circuit breaker 4 is electrically connected to circuits in the stationary portion 3 through disengageable disconnect contacts 5 of suitable design, the connection at 5 being broken and the circuit breaker isolated when the truck 1 is rolled towards the left, as viewed in Fig. 1.

The operating means for the breaker 4 may comprise any suitable arrangement, a simple manual operating mechanism being illustrated comprising a hand lever 6 pivoted to a stationary part 50 of the truck frame at 7, a connecting link 8, thrust transmitting toggle 9 and breaker operating lever 10. The breaker is closed by straightening of the toggle 9 and raising of the lever 10. Opening of the breaker may be effected manually

or by the usual trip coil at 11 through the trip lever 12 and latch indicated at 13, permitting the link 8 to move towards the left with respect to hand lever 6 by reason of the slot 14, thereby causing collapse of the toggle 9.

For the purpose of preventing destructive arcing at the disconnect contacts 5 by withdrawal of the truck while the breaker 4 is closed, suitable interlocking means is provided for tripping the breaker immediately upon withdrawal of the 10 truck. In the present instance a rod 15 is operatively connected to the rackout mechanism at 16 so as to actuate the trip lever 12 through lever 17 and crank 18 when the truck is withdrawn. The rackout mechanism comprises a worm gear 15 mounted on the truck and a coacting stationary rack, the worm gear being rotated by a socket wrench, or the like, exteriorly of the truck for moving the same with respect to the stationary portion 3.

The rod 15, which is normally biased downwards as by gravity or spring force, is likewise connected through a compression spring 19 to a pivoted latch 20 which is biased by the spring 19 so as to engage and hold, when in open circuit 25 position, the end 21 of a bellcrank 22 forming part of the toggle 9. The switchgear arrangement so far described is illustrated and disclosed in more detail in Patent No. 1,791,466 to H. G. French entitled "Electric Switching Devices".

A plurality of truck-type units may be arranged in a row to form a station as indicated by Fig. 2 which illustrates two trucks 1 and 1' movable with respect to the stationary circuit housing 3. In the interest of clearness, the plan view, Fig. 2, 35 omits the circuit breakers and operating mechanisms.

For the purpose of interlocking the operations of the breakers in the truck units 1 and 1', mechanical means are arranged between the operating mechanism of each breaker and the tripping mechanism of the other breaker, causing in the present instance tripping of one breaker upon closing of the other breaker and vice versa. The arrangement, while permitting both breakers to 40 be in open circuit position, permits but one breaker at a time to be in closed circuit position.

To this end a pair of independently rotatable shafts 23 and 24 are suitably mounted in the housing 3 in bearings 25, the shaft 24 being in 50 the form of a sleeve mounted on and freely rotatable with respect to the shaft 23. Each shaft is provided with means for interlocking the operating mechanism of one breaker and the tripping mechanism of the other breaker.

Referring more particularly to Fig. 3 wherein the breakers in the truck units 1 and 1' are referred to as A and B, respectively, a bellcrank 26 suitably mounted on the truck frame at 27 5 is connected through a link 28 to the bellcrank 22 of the operating toggle. The bellcrank 26 is likewise connected to a rod 29 which may engage in abutting relation a lug 30 secured to the shaft 24. As illustrated, the linkage arrangement connected to breaker A is in the closed circuit position so that opening of the breaker and clockwise 10 rotation of the bellcrank 26 merely moves the rod 29 away from abutting engagement with the lug 30 without rotating the shaft 24.

15 The tripping mechanism of the breaker B comprises a rod 15' on which is secured a collar 31' arranged to coat with a bifurcated arm 32' of a bellcrank 33' which is mounted on the truck frame at 34'. The other arm of the bellcrank 20 is connected to a rod 35' which, as in the case of rod 29, is arranged to abut a lug 30' secured to the shaft 24 in spaced angular relation with respect to lug 30. The relation between the lugs 30 and 30' is such that when the breaker A is 25 closed the rod 29 moves the lug 30 to such position that the lug 30' holds the rod 35' and bellcrank 33' in the position shown wherein the tripping rod 15' is in the tripping position. Accordingly, when the breaker A is in closed circuit position it is impossible to close breaker B by reason 30 of the inoperative condition of its tripping mechanism.

Assuming now that breaker A is opened, thereby causing movement of rod 29 away from lug 30, the downward bias on rod 15' resets the tripping mechanism of breaker B and causes clockwise rotation of lug 30' through crank 33'. Closing of the breaker B may now be effected, causing counterclockwise rotation of bellcrank 40 26' through the upward movement of rod 28' and movement of rod 29' towards the right to engage lug 36 which is secured to one end of the shaft 23. The shaft is accordingly rotated in a counterclockwise direction as is the lug 36' 45 which is secured to the other end of the shaft 23. As in the preceding instance, the lugs 36 and 36' are mounted in spaced angular relation on the shaft 23 so that when the breaker B is closed the tripping mechanism of breaker A is 50 held in tripped or inoperative position.

As in case of the tripping mechanism of breaker B, the tripping mechanism of breaker A is connected to the rod 15, the bellcrank 33 and rod 35 for coaction with the lug 36'. The bellcrank 33 is mounted on the frame 34 and is provided with a bifurcated arm 32 coacting with a collar 31 secured to the rod 15. Accordingly, counterclockwise rotation of shaft 23 in response to closing of the breaker B causes clockwise rotation of bellcrank 33 and elevation of the rod 15 to the tripping or inoperative position.

It will, therefore, be noted that either breaker may be closed when the other breaker is open and that when both breakers are open the tripping mechanism of each is operative so that either one may be closed. Closing of both breakers at the same time, however, is positively precluded.

The interlocking arrangement disclosed is particularly advantageous in installations where a plurality of interchangeable switch units of the draw-out type are required for the purpose of maintaining practical continuity of operation. An individual truck unit may immediately be 70 moved from the station without affecting the in-

terlocking arrangement between the same and another breaker and a similar unit may be moved without delay into operative position without requiring any connections or adjustments between the truck unit and interlocking arrangement. 5 Since each breaker of an interlocked pair is practically identical with the other, any breaker is interchangeable with any other in an installation using a number of pairs of interlocked breakers of like capacity. It will be apparent, of course, 10 that the interlocking arrangement above described is not limited to two breakers, and that, for example, breakers in pairs may be interlocked with respect to other pairs.

15 It should be understood that our invention is not limited to specific details of construction and arrangement thereof herein illustrated, and that changes and modifications may occur to one skilled in the art without departing from the 20 spirit of our invention.

What we claim as new and desire to secure by Letters Patent of the United States is:

1. In electrical switchgear including a plurality of circuit breakers, each breaker having a tripping mechanism and an operating mechanism, means for interlocking said breakers comprising a rotatable shaft operatively related to the operating mechanism of one breaker and the tripping mechanism of another breaker respectively, and a second rotatable shaft operatively related to the tripping mechanism of said first-named breaker and the operating mechanism of said other breaker respectively. 25

2. In electrical switchgear including a plurality of circuit breakers, each breaker having a tripping mechanism and an operating mechanism, means for interlocking said circuit breakers comprising a member operatively related to the operating mechanism of one of said breakers, a second member movable with said first member in 40 fixed relation thereto and operatively related to the tripping mechanism of another of said breakers, a third member operatively related to the tripping mechanism of said first-named breaker, and a fourth member movable with said 45 third member in fixed relation thereto and operatively related to the operating mechanism of said other breaker.

3. In electrical switchgear including a plurality of circuit breakers, each breaker having a tripping mechanism and an operating mechanism, means for interlocking said circuit breakers comprising a rotatable shaft, interlock members secured to said shaft in fixed spaced relation, means operatively connected to the operating 55 mechanism of one breaker and the tripping mechanism of another breaker arranged to engage in abutting relation said interlock members respectively, and a second rotatable shaft having similar interlock members arranged to engage 60 in abutting relation means operatively connected to the tripping mechanism of said first-named breaker and the operating mechanism of said other breaker respectively. 65

4. In truck type electrical switchgear including a plurality of movable circuit breakers, each breaker having a tripping mechanism and an operating mechanism, means for interlocking said circuit breakers comprising a rotatable shaft having a pair of interlock member secured thereto in spaced angular relation, one of said members arranged to engage in abutting relation means operatively connected to the closing mechanism of one of said breakers, the other of said members arranged to engage in abutting relation 70

75

means operatively connected to the tripping mechanism of another of said breakers, a second shaft arranged in concentric relation and freely rotatable with respect to said first shaft, a pair of interlock members secured in spaced angular relation to said second shaft, one of said last-named members arranged to engage in abutting relation means operatively connected to the tripping mechanism of said first-named breaker and the other member arranged to engage in abutting relation means operatively connected to the closing mechanism of the other breaker.

5. In a station including a plurality of similar

switchgear units of the draw-out type, each of said units having tripping means and actuating means, means for interlocking pairs of said units comprising means mounted independently of said units and actuated thereby for controlling the tripping operation of one unit in accordance with the actuating operation of the other unit, each of said units being freely withdrawable with respect to said interlocking means and interchangeable with any other of said units.
